ADDRESSING MACHINE

Charles N. Mazza, Framingham, Mass., assignor to Elliott Industries, Inc., Cambridge, Mass., a corporation of Delaware

Filed Apr. 6, 1962, Ser. No. 69,607

Term of patent 14 years

(Cl. D64—11)

FIG.1

FIG.2

FIG.5

FIG.4

FIG.3

FIG. 1 is a front perspective view of an addressing machine showing my new design;

FIG. 2 is a top plan view thereof;

FIG. 3 is a front elevational view; and

FIGS. 4 and 5 are opposite side elevational views thereof.

The back of the design is flat and unornamented.

I claim:

The ornamental design for an addressing machine, as shown and described.
